UNITED STATES PATENT OFFICE

2,009,116

STRETCHING AND TACKING IMPLEMENT

Harry T. McClure, Warwick, R. I., assignor to
 Boston Wire Stitcher Company, Portland,
 Maine, a corporation of Maine

Application February 10, 1932, Serial No. 591,999

8 Claims. (Cl. 1—45.6)

This invention relates to stapling devices or tackers, so-called, for use in fastening or attaching together two or more pieces of material or attaching materials to a relatively rigid mounting element, or for applying staples or similar fasteners to other articles penetrable thereby. The present invention relates particularly to a combined work-gripping and stapling or tacking implement whereby the work may be seized and held in desired position while driving the staple.

One object of the invention is to provide a manually-operable device or implement embodying stapling or tacking mechanism of any suitable type and having associated means by which the work may be gripped firmly at or near its edge to draw it into place, stretch the material on a surface, or to otherwise adjust and hold the work prior to and during the stapling operation.

Another object of the invention is to provide an improved implement of plier type having handles which may be gripped and actuated by one hand of the operator to cause the gripping means to seize the work for positioning it while leaving free the operator's other hand for manipulation of the staple-driving or tacking mechanism.

Another object of the invention is to provide an implement of the type specified having a peculiar form of handles by means of which it may be easily manipulated by a single hand to move the device bodily with the seized work, thus permitting the stretching or drawing taut of the work before stapling or tacking it to a support.

Another object of the invention is to provide an implement in the form of a holder adapted to rigidly but removably support the stapling mechanism of an ordinary hand stapling machine without material alteration in the design or structure thereof.

A further object of the invention is to provide a device of the type specified which is simple in construction, economical to manufacture, proof against derangement or getting out of order and efficient and durable in use.

Further objects of the invention are set forth in the following specification which describes a preferred form of construction of the device, by way of example, as illustrated by the accompanying drawing. In the drawing:

Fig. 1 is a perspective view of the improved device illustrating the gripping means in engagement with the edge of a work piece and the stapling mechanism in position for driving a staple therethrough;

Fig. 2 is a central longitudinal sectional view of the device shown in Fig. 1; and

Fig. 3 is a vertical transverse sectional view taken on line 3—3 of Fig. 2 looking in the direction indicated by the arrow.

In the embodiment of the invention as herein illustrated the stapling head and its mechanism is of a type employed in office or desk appliances but it is to be understood that the invention is adapted for use with other varieties of stapling or tacking means or with the head constructed as an integral part of the device.

The construction of the illustrated stapling mechanism is herein described briefly in so far as may be necessary for a clear understanding of its functions in the present use. The stapling mechanism shown in the present drawing is of a design and construction substantially like that described and illustrated in United States Letters Patent No. 1,584,788 granted May 18, 1926, with the elimination only of the base or desk support therefor. The stapling mechanism is mounted on an elongated arm or body 10 which is preferably of hollow construction to adapt it to serve as a magazine for carrying a supply of staples s. As herein shown, the stapling arm 10 comprises opposite side plates 11 riveted or welded to the sides of a hollow inverted U-shaped staple-core 12, across the top of which the staples s are straddled. The upper sides of the staple-core 12 are offset inwardly to provide spaces between them and the inner faces of the side plates 11 for receiving the legs of the staples, and the side plates 11 have in-turned flanges 13 which overlie the top of the staple-core to prevent the staples s from riding up thereon.

A staple-pusher 14, shown in Figs. 1 and 2, is adapted to straddle the sides of the core 12 in position at the rear of the series of staples s to slide the latter forwardly to feed the foremost staple into position beneath the staple-driver. As herein shown the staple-pusher 14 is attached to the end of a flat ribbon-like spring 15 which is wound into a volute coil 16 held on a core or mandrel 17 extending between upwardly projecting side-flanges 18 forming a part of the side plates 11 of the arm 10. The tension of the spring 15 serves to urge the staple-pusher 14 forwardly on the staple-core 12 to cause it to feed a fresh staple into position beneath the staple-driver 19 after the previously fed staple has been applied to the work.

The staple-driver 19, in the form of a flat metal plate, is carried by a plunger 20 which reciprocates at the front of the stapling arm 10, the lateral edges of the driver being formed with splines which slide in grooves in the inner faces of the

side plates 11. Secured to the top of the plunger 20 is a hand-rest or knob 21 adapted to receive the pressure of the operator's hand to slide the staple-driver 19 downwardly in driving the staples 5 through the work. Beneath the knob 21 is a helical spring 22, the lower end of which seats against a shelf or rest 23, thereby tending to maintain the plunger normally in raised position with the bottom edge of the staple-driver 19 10 above the top of the foremost staple in the series. It will be understood that the pressure of the staple-pusher 14 holds the foremost staple pressed against abutments 24 at the forward end of the arm 10 with the legs of this staple opposite the 15 grooves in which the staple-driver 19 slides, thereby preventing the staple from dropping down out of position until it is acted upon by the driver.

The structure and arrangement of the stapling mechanism as above described are in accordance 20 with a well-known type of device now in common use, but it is to be understood that this part of the apparatus is not directly related to the present invention and may take other forms. For example, means for driving tacks or brads may be 25 substituted in its place.

As hereinbefore stated, the invention is particularly concerned with the provision of an improved device or implement embodying a suitable 30 form of stapling or tacking mechanism and means cooperating therewith whereby the work may be drawn into position to be fastened to a support or other object. Examples of the uses to which the implement may be applied are: the stretching and mounting of skins or pelts on a rigid backing or board, and the stretching and tacking of screen-cloth to a window or door frame. These 35 stated purposes are mentioned only as examples, however, it being understood that the device is applicable to use in many other arts requiring either 40 the holding or stretching of materials preparatory to and during fastening them in place.

Referring further to the accompanying drawing, the stapling arm 10 is herein shown as being carried by the forward end 25 of one of a pair 45 of pivotally connected handle-members 26 and 27. The members 26 and 27 are preferably constructed of light cast metal, such as aluminum or aluminum alloy, and are hinged together to provide pairs of cooperating arms or 50 extensions at each side of their fulcrum or pivotal axis. One pair of arms constitute the means for supporting the stapling mechanism and for providing work-gripping jaws, while those of the other pair are shaped to provide handles by means 55 of which the gripping jaws are actuated in the manner of pliers. The member 27 is made of greater transverse dimension at its forward end, indicated by the reference numeral 28, and is suitably apertured to provide a substantially rectangularly shaped opening 29 therethrough. The lateral sides 30 of the other member 26 are dimensioned to fit within the inner faces of the sides 31 longitudinally bounding the opening 29 60 in the member 27. In assembling the parts the member 26 is inserted through the opening 29 of the member 27 and pivot-pins 32 riveted through aligned holes 33 and 34 provided in each of the sides 31 and 30.

The forward extremities of the sides 31 of the 70 member 27 are connected by an integral, transverse bridge-piece 35 which lies underneath the forward arm of the member 26 and the stapling mechanism carried thereby. Secured to the bridge 35 by rivets 36 or other suitable means is a 75 forwardly-extending bottom grip-plate or jaw 37,

the purpose of which will be hereinafter more fully explained.

The rearward arms or extensions of the members 26 and 27 are shaped to provide handles for grasping the implement by one hand to operate it in the manner of a pair of pliers. One or both of the handles may be provided with a curved finger or hook, such as indicated by the reference numeral 38, to prevent the hand from slipping when the device is pulled to stretch or draw taut the 10 material gripped thereby. As above indicated, the member 26 is formed to adapt it to mount a stapling mechanism of any suitable type.

In the embodiment of the stapling mechanism as herein shown the stapling arm 10 is constituted 15 as an elongated body of substantially rectangular cross section. Consequently, the forward end of the member 26 is constructed with a longitudinally extending pocket or recess complementary to the outer configuration of the stapling arm 10. To 20 provide for repair or replacement of the stapling unit the present invention contemplates the provision of means whereby it may be removed from and replaced on the implement at will. Accordingly, the recess in the member 26 for receiving 25 the stapling arm 10 is open at one end to permit the arm to slide thereinto and be withdrawn therefrom. More specifically, the member 26 is recessed longitudinally to provide a pocket 40 having a flat bottom 41 and sides 30 with overhanging upper flanges 43, the forward end 44 of the pocket being open. The sides 30 and flanges 43 are adapted to extend substantially the entire length of the arm 10, while the bottom 41 projects forwardly only about one-half the length 35 of the arm. The arm 10 preferably has a close fit within the interior of the pocket 40 to rigidly hold the stapling mechanism in place on the member 26.

Means are provided for releasably locking the 40 stapling arm 10 to the member 26 and in the present embodiment of the invention the locking means comprises a flat leaf-spring 45 riveted at 46 to the floor or bottom 41 of the pocket 40 in the member. The forward end of the spring 46 45 is provided with a detent latch or keeper 47 which engages with a transverse slot 48 provided in the bottom of the arm 10. The arm 10 has been described as comprising side plates enclosing a hollow staple-core 12. In the usual construction 50 the several parts of the arm 10 are held together by means of a channel-strip 49 which has its sides welded or otherwise suitably fastened to the sides of the staple-core 12. In the present form of construction the lower channel or recess in the strip 49 is provided with a filler strip or plate 50, in which is formed the detent slot 48. Rearwardly of the slot 48 the plate 50 is beveled off at 51 to adapt it to ride over the edge of the latch 47 on the spring 45 to depress the latter. In assembling 60 the stapling mechanism on the member 26 the rearward end of the arm 10 is slid rearwardly within the pocket 40 until the detent-latch 47 engages with the slot 48 in the under side of the arm. The stapling mechanism will thus be properly positioned on and locked to the member 26 in operative position at the forward end of the implement. To remove the arm 10 and the stapling mechanism carried thereby from the implement it is merely necessary to depress the spring 70 45 by engaging its outer end, thus freeing the detent-latch 47 from the slot 48.

The lower grip-plate or jaw 37 which, as before mentioned, is carried on the member 27, extends 75 forwardly therefrom to a position just short of

the outer end of the stapling arm 10, that is, closely adjacent to the path of movement of the staple-driver 19. By this form of construction there is provided between the top of the jaw 37 and the bottom of the forward end of the arm 10 a pair of gripping surfaces by which the piece of work *w* may be seized to position it for stapling. It is of course obvious that pressure applied to the ends of handles on the members 26 and 27 by the hand of an operator will cause a movement of the jaw 37 toward the bottom of the arm 10. To provide a secure grip of the jaws on the edge of the work, such as an animal pelt or a piece of leather or fabric, the jaw 37 and arm 10 are provided with teeth or serrations 52 and 53 extending laterally of their opposed faces. The serrations 53 are cut transversely of the bottom of the side plates 11 of the arm 10 at the forward end thereof and in the bottom surface of the filler plate 20 50 which is extended to the forward end of the arm.

It will be observed from the foregoing description that the invention provides an implement for gripping skins, leather, fabric, screen-cloth and other work-pieces at their edge portions to render it convenient to stretch and position the same in stapling or tacking them to a support. After the material has been drawn into position or stretched across a frame or support, with the implement held in one hand, the operator presses on the knob 21 with the other hand to slide the driver 19 downwardly to drive a staple through the material and into the support therebeneath. This operation may be repeated as required with the staples or other fasteners fed automatically to the applying means as long as a supply remains in the magazine.

Particular attention is directed to the construction of the work-gripping jaw 37 of the implement which consists of a relatively thin plate having a serrated or roughened upper surface adapted to cooperate with the opposed gripping surface 53 on the stapling arm 10. The jaw 37 is purposely made as thin as is practicable for its required function to permit the work-piece held thereby and the stapling mechanism to be brought relatively close to the object upon which the material is to be tacked or fastened. It will be observed by reference to Fig. 1 of the drawing that the work-piece gripped by the jaws is brought substantially to the level of the mounting board and the staple-driver is thus rendered capable of driving a staple or tack to the desired depth, that is, with the work-piece in close contact with its mounting.

It will also be observed by reference to the drawing that the handles at the rear end of members 26 and 27 are so constructed as to lie above the plane of the lower surface of the gripping jaw 37 when the device is in operative position, thus permitting the implement to be positioned close to the surface of a mounting element or frame to which a skin, pelt, screen cloth or the like is to be attached. Furthermore, this novel construction and arrangement of the handles with respect to the underside of the lower gripping jaw and the stapling mechanism permits the placement of the implement at any point upon a substantially flat surface with the staple-driver or tacker in the proper operating position. By forming the finger or hook 38 with its lower end above the surface plane of the bottom of jaw 37 an operator may hold the entire implement in surface contact with an article without cramping the fingers. This feature is

found to be of especial advantage in mounting skins or pelts upon a rigid backing when it is desired to apply the staples or tacks in the central area thereof.

The present device is simple in structure, inexpensive to manufacture, and efficient in use for the above-mentioned and other purposes. It is light in weight and compact in size to permit the manipulation of the work-gripping jaws by means of one hand of the operator and thus leave the other hand free to operate the mechanism for driving the staples. In certain instances where it is not desired to hold the work-piece between the gripping jaws the handles may be held in closed position and the device placed directly upon the work with the bottom of the jaw member 37 resting thereon.

While there is herein illustrated and described one preferred embodiment of the device it is to be understood that various modifications may be made in the structure and arrangement of the parts thereof without departing from the spirit or scope of the invention. Therefore, without limiting myself in this respect, I claim:

1. In an implement of the character specified the combination of a pair of pivoted members, jaws operative by movement of the pivoted members for seizing the edge of a piece of material, means for releasably attaching a stapling device to one of said member, means for carrying a supply of fasteners in said stapling device, and a driver on the stapling device reciprocable across the side of the jaws to drive the fasteners through the material and into a support.

2. In an implement of the character described, the combination of a magazine for carrying a supply of fasteners, a driver for driving the fasteners through the work, means for successively feeding the fasteners to the driver, a holder for said fastener-applying mechanism comprising a pair of handle-members pivotally connected together with one of said members formed with a longitudinally-extending opening at its forward end adapted to receive the magazine of the fastener-applying mechanism, and means for retaining said magazine in said opening.

3. In an implement of the character specified, the combination of a fastener-applying unit, a pair of plier-members, means operative by movement of the plier-members for gripping the edge of a piece of material, and means for releasably mounting the fastener-applying unit on the implement in position to apply the fasteners adjacent to the edge of the material held in the gripping means.

4. In an implement of the character specified, the combination of a stapling unit, a pair of plier-members, jaws operative by the movement of the plier-members for gripping the edge of a piece of material, one of said members formed with a pocket for receiving the stapling unit, and means for releasably attaching the stapling unit to the plier-member.

5. In an implement of the character specified, the combination of a pair of plier-members, jaws operative by the movement of the plier-members for seizing the edge of a piece of material, one of said members formed with a longitudinally-extending opening, a fastener-applying unit slidably mounted within the opening in said member, and detent-means for releasably securing the fastener-applying unit in place in the opening in said member.

6. In an implement of the character specified, the combination of a pair of pivoted plier-mem-

- bers, jaws operative by movement of the plier-members for gripping the edge of a piece of material, one member being of hollow construction, a stapling-head fitted within the hollow member, 5 latching means for retaining the stapling-head within the hollow member, a staple-driver reciprocable on said head for driving the staples into the work, and means for successively feeding staples into position beneath the staple-driver.
- 10 7. In combination with a device having means for applying fasteners to the work and a magazine for supplying fasteners to the applying means, a handle member having a slotted portion adapted to receive the fastener-applying device, latching means for releasably retaining said device within the opening of said handle member, and a second handle member pivoted to the first member and having a jaw extending forwardly
- 15

from its pivot for cooperation with the under side of the device to grip the material to be fastened.

8. In combination with a stapling device having a head with mechanism therein for applying staples, a magazine for containing a supply of staples and means for feeding said staples to the applying mechanism; a handle member having a slotted forward end adapted to receive the magazine of the stapling device, a latch for retaining said stapling device within the slotted end of said member, and a second handle member pivoted to the first member and provided with a jaw underlying the forward end of the stapling device to adapt it to cooperate therewith to seize 10 the work to hold it while it is being stapled.

HARRY T. McCLURE.
